UNITED STATES PATENT OFFICE.

FREDERICK WINK, OF PHILADELPHIA, PENNSYLVANIA, ASSIGNOR TO
THOMAS DOLAN AND R. WILLIAMS, JR., OF SAME PLACE.

DESIGN FOR SHAWL-PATTERN.

Specification forming part of Design No. 6,859, dated September 2, 1873; application filed August 9, 1873.
[Term of Patent 3½ years.]

X.

To all whom it may concern:

Be it known that I, FREDERICK WINK, of the city and county of Philadelphia, State of Pennsylvania, have invented a Design for Shawl-Pattern, of which the following is a specification:

The figure in the accompanying drawing clearly illustrates my design, which consists of two stripes, A and B, upon a plain ground, D, the stripe A having a central rib, *a*, and a rib, *b*, at each side of the same, ornamented by parallel rows of dashes and dots, and the stripe B being similarly ornamented by a central rib, *d*, both of the said stripes being otherwise composed of a series of plain parallel

stripes, bars, or ribs of varying widths and different shades or colors, some blended into each other and others strongly constructed, as shown.

Irrespective of the colors employed, I claim—
The design for a shawl-pattern, as described, and as represented in and by the accompanying drawing.

In testimony whereof I have signed my name to this specification in the presence of two subscribing witnesses.

FRED. WINK.
